UNITED STATES PATENT OFFICE.

KONRAD BOTZ, OF NEW YORK, N. Y.

TRANSMITTER OR RECEIVER.

1,270,920.

Specification of Letters Patent. Patented July 2, 1918.

Application filed June 28, 1917. Serial No. 177,491.

To all whom it may concern:

Be it known that I, KONRAD BOTZ, a citizen of Germany, (first naturalization papers having been obtained,) and a resident of 5 the city of New York, borough of Manhattan, in the county and State of New York, have invented a new and Improved Transmitter or Receiver, of which the following is a full, clear, and exact description.

10 This invention relates to a device adapted to be used in telephony for converting sound waves into electrical impulses or electrical impulses into sound waves.

15 The invention has for its general object to improve the construction and operation of transforming devices of this character so as to be reliable and efficient in use, and possess extreme sensitiveness and superior 20 sound or electrical impulse-transforming qualities.

A more specific object of the invention is the provision of a transmitter or receiver of the "diaphragm" type, which has 25 operationally connected with the diaphragm an oscillator element in the form of a helical cone of magnetic and current-conducting material, which so influences the magnetic field when the diaphragm is actuated that 30 current impulses will flow through the circuit in which the oscillator is connected, and furthermore the passage of electric impulses through the magnetic oscillator so influences the magnetic field that the diaphragm will 35 be oscillated to emit the original sounds which set up the electrical impulses in the metallic circuit of an ordinary telephone system or in the ether in a wireless telephone system.

40 With such objects in view, and others which will appear as the description proceeds, the invention comprises various novel features of construction and arrangement of parts which will be set forth with particularity in the following description and claims appended hereto.

In the accompanying drawings, which illustrate one embodiment of the invention and wherein similar characters of reference 45 indicate corresponding parts in all the views,

Figure 1 is a central vertical section of the device;

Fig. 2 is a diagrammatic view illustrating the magnetic field and its relation to the

convolutions of the conical helix that 55 forms the oscillator;

Fig. 3 is a front view with the mouth-piece partly broken away;

Figs. 4 and 5 are diagrammatic views 60 of the telephone circuits with the transmitting and receiving means therein.

Referring to the drawing, 1 designates a mica or other non-metallic diaphragm which is clamped at its periphery between the mouth or ear-piece 2 and conical shell 65 or casing 3. This casing has a flange 4 at its smaller end so as to constitute a spool on which is wound a magnetizing coil 5 that has its terminals 6 and 7 connected with a source of continuous current 8, as 70 shown in Fig. 4. Within the casing 3 is the oscillator 9 which is a conical helix made of iron, steel or other material which is both magnetic and conductive. One end of the helix is connected by a button or suitable fastening 10 to the center of the diaphragm 1, and also connected with this button is a flexible conductor 11 which passes through an eyelet 12 in the piece 2, so that the helix or oscillator can be connected with 75 a circuit.

The smaller end of the helix is connected at 13 with the back of the casing 3, where a binding post 14 is provided, whereby the helix can be connected with an outside circuit. It will thus be seen that the oscillator 85 is supported only at its ends, and all the convolutions are free from each other and out of contact with any conducting material. When the diaphragm oscillates, the 90 convolutions will move relatively toward and from each other, which will vary the intensity of the magnetic field produced by the winding 5, and this variation will cause an electromotive force to be set up in the 95 convolutions, whereby a high frequency current will be generated when the diaphragm 1 is oscillated by the impingement of sound vibrations thereon. If current impulses pass through the oscillator the field 100 of force generated by the current flowing through the convolutions will react on the field developed by the coil 5, and motion will be imparted to the diaphragm that will set up sound vibrations. In Fig. 2 the 105 arrow lines represent the field of force developed by the winding, whereby the convolutions of the oscillator are magnetized.

The oscillator 9 can be connected with telephone lines 15 and 16 through the usual induction coil or transformer T, as shown in Fig. 4, or it may be connected directly with the line wires 17 and 18, as shown in Fig. 5. The oscillators in this figure are represented as permanently magnetic, so that a field coil equivalent to 5, Figs. 1 and 4, will not be required. In this case the vibration of the diaphragm 1 causes the convolutions of the oscillator to move toward and from each other, which results in a rapid change in the density of the magnetic field, which in turn causes a high frequency current to be developed in the conductive oscillator. At the receiving end of the circuit the high frequency current impulses flowing through the convolutions of the oscillator will cause the oscillator to mechanically oscillate and vibrate the diaphragm, which sets up sound vibrations.

From the foregoing description taken in connection with the accompanying drawings, the advantages of the construction and method of operation will be readily understood by those skilled in the art to which the invention appertains, and while I have described the principle of operation, to-

gether with the device which I now consider to be the best embodiment thereof, I 30 desire to have it understood that the device shown is merely illustrative and that such changes may be made when desired as fall within the scope of the appended claims.

Having thus described my invention, I 35 claim as new and desire to secure by Letters Patent:

1. A device of the class described including a non-metallic diaphragm, a conical helix of conducting and magnetic material 40 having one end fastened to the diaphragm and the other end fixed, means for connecting the ends of the helix in an electric circuit, and means for enveloping the helix in a magnetic field. 45

2. A device of the class described including a non-metallic diaphragm, a conical helix of conducting and magnetic material having one end fastened to the diaphragm and the other end fixed, means for connecting the ends of the helix in an electric circuit, a magnetizing coil surrounding the helix, and a source of continuous current 50 connected with the coil. 55

KONRAD BOTZ.
